[57] CLAIM

The ornamental design for an automobile body section, as shown and described.

DESCRIPTION

FIG. 1 is a perspective view of an automobile body section showing my new design;

FIG. 2 is a right side elevational view thereof, the left side being a mirror image of the right side shown herein;

FIG. 3 is a rear elevational view thereof; and

FIG. 4 is a top plan view thereof.

The broken lines in the drawing are for illustrative purposes only.
